PAN-ADVANCE ADJUSTING MECHANISM
FOR OVEN FEEDING MACHINES

Robert L. Brosemer, Sacramento, Calif.

Application April 26, 1948, Serial No. 23,193

9 Claims. (Cl. 214—18)

1

This invention has for an object certain improvements in the oven feeding machine as shown and described in copending application for United States Letters Patent, Serial No. 715,383, filed December 11, 1946, now Patent No. 2,450,111, dated September 28, 1948.

In such prior application the oven feeding machine included a power-actuated pusher assembly adapted to advance loaded baking pans from a table in front of the oven into the latter in predetermined order; the pusher assembly, however, having a fixed point of advance. It has been found that a variable point of pan-advance is desirable.

It is therefore an object of the present invention to provide the oven feeding machine with a pan-advance adjusting mechanism of novel construction and operation; such mechanism being arranged so that the extent of advance of loaded pans from the supporting table and into the oven can be regulated, selectively, by the operator, and as working conditions and the size of the pans may require.

Another object of the invention is to provide a pan-advance adjusting mechanism, as above, which includes a rack and pinion device corresponding to each swing arm unit which the machine includes to actuate the pusher assembly; each device being operative to shift the pivot point of the corresponding swing arm unit toward or away from the oven to thus alter the point of pan advance of said pusher assembly relative to said oven.

A further object of the invention is to provide a practical pan-advance adjusting mechanism for oven feeding machines, and one which will be exceedingly effective for the purpose for which it is designed.

These objects are accomplished by means of such structure and relative arrangement of parts as will fully appear by a perusal of the following specification and claims.

In the drawings:

Fig. 1 is an end elevation of an oven feeding machine embodying the present invention; the adjusting lever being shown in full lines in position for maximum pan advance, and in dotted lines in position for minimum pan advance.

Fig. 2 is a transverse sectional elevation of the machine showing the same as set for maximum pan advance.

Fig. 3 is a similar view but shows the machine as set for minimum pan advance.

Fig. 4 is an enlarged fragmentary cross section of one of the rack and pinion devices,

2

Fig. 5 is an enlarged end view of one of the rack and pinion devices.

Referring now more particularly to the characters of reference on the drawings, the general assembly of the oven feeding machine is as shown in the aforesaid copending application, Serial No. 715,383, and comprises an upstanding frame 1 of skeleton type adapted to seat on the floor directly in front of the baking oven.

At the top the frame 1 is fitted with a horizontal pan receiving or supporting table 2 adapted to be disposed in direct alinement with the door of the oven and through which door the pans are to be fed by the machine.

The pan receiving and supporting table 2 comprises a multiplicity of longitudinally extending, transversely spaced bars 3 whereby said table is of longitudinally slotted configuration. The bars 3 are supported, at their rear ends, by an upstanding plate 4, while the forward ends of said bars are supported by transversely spaced, upstanding fingers 5.

The pans (not shown) are fed from atop the table 2, through the oven door into the oven, by means of the following described reciprocating feed mechanism or pusher assembly:

Beneath the longitudinally slotted table 2, the machine includes, adjacent each end thereof, a horizontal, longitudinally extending guide rail 6 of laterally inwardly facing channel configuration, and said guide rails are connected by a cross bar 7 fitted, at the ends, with slide blocks 8 which run in corresponding ones of the channel shaped rails 6, whereby the cross bar 7 may be advanced, and retracted, relative to the oven. The guide rails 6 are mounted, for vertical movement or reciprocation, by guide units, indicated generally at 9, and which are fixed in connection with said guide rails and work in cooperation with the corner posts of the frame 10.

The cross bar 7 is non-turnable and carries a plurality of upwardly and forwardly curved pusher fingers 11 positioned to work through the slots between the bars 3. When the guide rails 6 are in raised position, the pusher fingers 11 project above the table 10 for working and advancing engagement with a pan, whereas when said guide rails 6 are lowered, the pusher fingers 11 are below the table for free retracting movement.

The assembly of the guide rails 6, cross bar 7, and the pusher fingers 11, is recurrently raised up and down, i. e. vertically reciprocated, by the following arrangement:

A horizontal cross shaft 12 extends through,

and is supported by, the frame 1 some distance below the table 2; said cross shaft being driven by any suitable means. Adjacent each end thereof of the horizontal cross shaft 12 carries a rotary cam 13, and a vertical plunger 14, having a roller on its lower end, cooperatively engages said cam. The plunger 14 is carried in a guide sleeve 15 mounted in the frame 1, and at its upper end the plunger 14 is attached to the corresponding guide rail 6; there being spring means (not shown) within the guide sleeve 15 urging the plunger downwardly whereby to normally tend to lower the corresponding guide rail 6.

The cams 13, of which there is one corresponding to each guide rail 6, are of matching configuration and are formed so that with each revolution of the horizontal cross shaft 12, said cams act to raise the pusher fingers 11, maintain them in such raised position for a certain time, and then permit them to retract under the action of the spring-urged plungers 14.

The assembly of the slide blocks 3, cross bar 7, and the pusher fingers 11, is reciprocated back and forth, i. e. advanced and retracted in successive and recurring order, by upstanding swing arm units, indicated generally at 16, corresponding to and adjacent the rotary cams 13. Each swing arm unit 16 is mounted in the frame for swinging movement in a longitudinal vertical plane; the axis of swinging movement of each such unit being provided, at its lower end, by an adjustable pivotal mount, indicated generally at 17, and which is hereinafter described in greater detail.

Each swing arm unit 16 is telescopic and includes an upper section 18 which is mounted for vertical sliding motion relative to the lower section 19. The upper section 18 of each swing arm unit 16 is turnably connected, at its upper end, with the cross bar 7, whereby upon to and fro swinging of the arm units 16 said cross bar 7 and the pusher fingers 11 are reciprocated in a path which includes a pan advancing stroke above the table 2, and a retracting stroke below said table.

Such swinging of the swing arm units 16, which are alined transversely of the machine, is accomplished by a crank 20, corresponding to each such unit and mounted on the cross shaft 12. Each crank 20 includes a crank pin 21 carried in a slide block 22 running in a longitudinal slot 23 in the corresponding swing arm unit 16.

Thus, as the cross shaft 12 and cranks 20 rotate, the arm units 16 swing back and forth in a longitudinal vertical plane to advance and retract the pusher fingers 23 through the path or cycle above described. The cams 13 are disposed relative to the cranks 20 so that at the beginning of each forward or advance movement of the arm units 16, the guide rails 6 are raised, projecting the pusher fingers 11 above the table 10 for pan engagement and advancement. The guide rails 6 remain raised until the arm units 16 reach the forward limit of their movement whereupon said rails are dropped by the cams so that the fingers 11 move downward below the table for the retracting portion of each cycle.

When the pusher assembly, including the pusher fingers 11, reaches the forward limit of its pan advancing stroke, said fingers project somewhat beyond the front edge of the table 2. In the prior embodiment of the invention the forward point of advance of said fingers was fixed and no adjustment was possible. It has since been found desirable that the machine be adjust-

able to regulate or vary the forward point of advance of the pusher fingers 11, whereby to compensate for pans of different widths etc., and to the end that such pans be advanced the proper distance into the oven through its door.

To accomplish this the present invention contemplates the employment of the pivotal mounts 17, by means of which the axis of swinging movement of the arm units 16 may be adjusted in a direction toward, or away from, the oven, whereby to vary the forward point of advance of the fingers 11.

A horizontal cross shaft 24 is mounted in the frame 1 adjacent its lower end, and adjacent each end said cross shaft serves as the pivotal axis for the corresponding swing arm unit 16; the latter being journaled on the shaft.

On opposite sides of each swing arm unit 16 the cross shaft 24 is fitted with a pinion 25 which rests on, and runs in mesh with, a corresponding horizontal, longitudinally extending rack 26. Each rack 26 is rigidly secured in the lower end portion of an upstanding, rectangular, cage-frame 27 fixed in connection with the main frame.

Each of the pinions 25 is formed with a circumferential groove 28 intermediate its ends, and a hold-down and stabilizing saddle plate 29, having a substantially semi-circular, downwardly opening cut-out 30 therein, engages in such circumferential groove 28 from above. Each saddle plate 29 is rectangular at its upper portion and engages in longitudinally slidable relation between a transversely spaced pair of guide bars 31 in the cage-frame 27, and is engaged from above by a bearing strip 32 whose alinement is maintained by adjustment screws 33 threaded through the top bar 34 of said cage-frame. The adjustment screws 33 include lock nuts 35.

With the above arrangement the saddle plates 29 are slidable longitudinally, but are maintained against upward displacement, so as to assure that the pinions 25 mesh at all times with the corresponding racks 26 without undue vertical play.

At one end the cross shaft 24 is fitted with a radial adjusting lever 36 which upstands beyond one end plate 37 of the machine; such lever co-operating with a latching quadrant 38. The latching quadrant 38 is arranged so that the lever 36 may be set in selective positions therealong, as shown.

It will be recognized that upon swinging of the lever in one direction or the other, corresponding rotation is imparted to the cross shaft 24, running all the pinions 25 either forwardly or rearwardly on the racks 26.

The effect of this adjustment of the pinions 25 on the racks 26 is to either advance or retract the shaft 24; i. e. the axis of pivotal motion of the swing arm units 16 relative to the oven, without appreciably affecting or altering the stroke of said arm units 16, and without requiring adjustment of the actuating means therefor. By such adjustment of the pivotal axis of the arm units 16, the forward point of advance of the pusher assembly, including the push fingers 11, can be varied accurately and to such selective extent as the operator may deem necessary.

In short, as the axis of the swing arm units 16 is moved to a rearward position, as in Fig. 2, the pusher fingers 11 have a maximum forward point of advance, and conversely when said axis is moved to a forward position, as in Fig. 3, the

pusher fingers 11 have a minimum point of forward advance.

Thus, by the simple manipulation of the radial adjusting lever 36, the operator can cause the pans to be advanced from the table 2, through the oven door, and into the oven, to differential extents.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. In an oven feeding machine, a pan support and a power actuated pusher assembly operatively arranged to advance a pan from the support in a predetermined direction and to a selectively variable point of pan advance; said power actuated pusher assembly including a pivotally mounted swing arm unit, the pivotal mount for said swing arm unit incorporating a rack and pinion device arranged to advance or retract the axis of the swing arm unit to thereby vary said point.

2. In an oven feeding machine, an upstanding frame, a pan supporting table on the frame, a pusher assembly operatively arranged to engage a table supported pan from the rear and to advance the pan in a predetermined direction from the table, said pusher assembly including a swing arm unit disposed under the table for swinging motion in a longitudinal vertical plane, a pivotal mount connected between the swing arm unit and the frame, said pivotal mount being arranged for adjustment to advance or retract the axis of swinging motion of the swing arm unit, and power actuated means connected to the swing arm unit to oscillate the same; the pivotal mount connecting with the lower end of the swing arm unit, and the power means connecting with said swing arm unit intermediate its ends.

3. In an oven feeding machine, an upstanding frame having a pan supporting table thereon, and a power actuated reciprocating pusher assembly cooperating with the table to engage a pan from the rear and to advance the pan in a predetermined forward direction and for a selectively variable distance; said pusher assembly including an upstanding swing arm unit below the table, a cross shaft on which the swing arm unit is pivoted for swinging motion in a longitudinal vertical plane, said shaft being movable forwardly or rearwardly, a pinion on the shaft, a rack fixed on the frame, the pinion meshing with the rack, means to rotate the shaft, and power means connected to the arm unit to oscillate the same.

4. In an oven feeding machine, an upstanding frame having a pan supporting table thereon, and a power actuated reciprocating pusher assembly cooperating with the table to engage a pan from the rear and to advance the pan in a predetermined forward direction and for a selectively variable distance; said pusher assembly including an upstanding swing arm unit below the table, a cross shaft on which the swing arm unit is pivoted for swinging motion in a longitudinal vertical plane, said shaft being movable forwardly or rearwardly, a pinion on the shaft, a rack fixed

on the frame, the pinion meshing with the rack, means to rotate the shaft, and power means connected to the arm unit to oscillate the same; there being guide and hold-down means cooperating with the pinion to maintain the same in mesh with the rack while permitting the pinion to run along said rack.

5. In an oven feeding machine, an upstanding frame having a pan supporting table thereon, and a power actuated reciprocating pusher assembly cooperating with the table to engage a pan from the rear and to advance the pan in a predetermined forward direction and for a selectively variable distance; said pusher assembly including an upstanding swing arm unit below the table, a cross shaft on which the swing arm unit is pivoted for swinging motion in a longitudinal vertical plane, the cross shaft being shiftable lengthwise of the path of movement of the push assembly and disposed at the lower end of the swing arm unit, a pinion on the cross shaft, a longitudinal rack on the frame with which the pinion meshes, a hold-down and guide cooperating with the pinion while permitting the same to travel along the rack, and power means connected to the swing arm unit intermediate its ends.

6. In an oven feeding machine, an upstanding frame having a pan supporting table thereon, and a power actuated reciprocating pusher assembly cooperating with the table to engage a pan from the rear and to advance the pan in a predetermined forward direction and for a selectively variable distance; said pusher assembly including an upstanding swing arm unit below the table, a cross shaft on which the swing arm unit is pivoted for swinging motion in a longitudinal vertical plane, the cross shaft being shiftable lengthwise of the path of movement of the push assembly and disposed at the lower end of the swing arm unit, a pinion on the cross shaft, a longitudinal rack on the frame with which the pinion meshes, a hold-down and guide cooperating with the pinion while permitting the same to travel along the rack, and power means connected to the swing arm unit intermediate its ends; said power means including another cross shaft above said first named cross shaft, said other cross shaft being driven and a crank on said other cross shaft including a crank having a crank pin, the swing arm unit being a longitudinal slot in which said crank pin engages.

7. In an oven feeding machine, an upstanding frame having a pan supporting table thereon, and a power actuated reciprocating pusher assembly cooperating with the table to engage a pan from the rear and to advance the pan in a predetermined forward direction and for a selectively variable distance; said pusher assembly including an upstanding swing arm unit below the table, a cross shaft on which the swing arm unit is pivoted for swinging motion in a longitudinal vertical plane, the cross shaft being shiftable lengthwise of the path of movement of the push assembly and disposed at the lower end of the swing arm unit, a pinion on the cross shaft, a longitudinal rack on the frame with which the pinion meshes, the pinion having a circumferential groove intermediate its ends, a saddle plate engaged in said groove opposite the rack, guide and holding means guiding the saddle plate for longitudinal sliding motion but holding the plate against escape from the groove, and power means connected to the swing arm unit intermediate its ends.

8. In an oven feeding machine, an upstanding frame having a pan supporting table thereon, and a power actuated reciprocating pusher assembly cooperating with the table to engage a pan from the rear and to advance the pan in a predetermined forward direction and for a selectively variable distance; said pusher assembly including an upstanding swing arm unit below the table, a cross shaft on which the swing arm unit is pivoted for swinging motion in a longitudinal vertical plane, the cross shaft being shiftable lengthwise of the path of movement of the push assembly and disposed at the lower end of the swing arm unit, a pinion on the cross shaft, a longitudinal rack on the frame with 15 which the pinion meshes, a hold-down and guide cooperating with the pinion while permitting the same to travel along the rack, and power means connected to the swing arm unit intermediate its ends; there being a radial hand lever on the cross shaft accessible from exteriorly of the frame, and means to hold said lever in selective positions of adjustment.

9. In an oven feeding machine, an upstanding frame, a pan-supporting table on the frame, a 25 pusher assembly operatively arranged to engage

5 a table-supported pan from the rear end to advance the pan along the table in a predetermined direction, said pusher assembly including a swing arm unit, means pivotally mounting the swing arm unit in connection with the frame for swinging motion in a longitudinal vertical plane, power actuated means connected to the swing arm unit to reciprocate the latter and means to adjust the pivotal mounting means to a selective extent to advance or retract the axis of swinging motion of the arm unit whereby to thus vary the forward point of pan advance; said last named means comprising a rack and pinion device included in said pivotal mounting means.
